UNITED STATES PATENT OFFICE

2,339,112

DISPLAY CONTAINER

Paul Roberts, Sandusky, Ohio, and John W. White, Chicago, Ill., assignors to The Hinde & Dauch Paper Company, Sandusky, Ohio, a corporation of Ohio

Application July 12, 1940, Serial No. 345,126

1 Claim. (Cl. 206—44)

This invention relates to a folding display carton, usually made of corrugated board, which is adapted either for shipping or for display purposes without requiring repacking of the contents, and is an improvement upon the invention of one of the present applicants, Paul Roberts, disclosed in Patent No. 2,168,240 issued August 1, 1939. The present invention, like that of the previous patent, relates to a carton having a top which can be raised to become a display back, and side wings which join the back and so form display sides. The present invention is directed to means for better displaying samples of the merchandise in the carton and for keeping the back and sides upright when set up for display, irrespective of the amount of merchandise in the carton.

In the accompanying drawing:

Fig. 1 is a perspective view of the carton, with any form of the present invention applied thereto, closed and sealed ready for storage or shipping;

Fig. 2 is a perspective of a carton set up for display, using one form of the present invention;

Fig. 3 shows the carton of Fig. 2 in a position part way between closed and opened;

Fig. 4 is an interior transverse vertical section on plane 4—4 of Fig. 2; and

Fig. 5 is a detail vertical section through the closed lid and wings, plane 5—5, Fig. 1.

The present improved carton in its general appearance and organization is similar to that of Patent No. 2,168,240, having a conventional bottom construction to which no reference characters are applied in the present disclosure, a back 1, sides 2, drop front, wings, back and a top lap. The drop front comprises a permanent panel 4 and a movable or drop panel 5, having a top lap 6 (herein conveniently shown as a full lap) bendably attached to its outer edge, said lap being adapted either to fit as a top lid of the box when closed or to fit under the box when open for display, as seen in Figs. 1 and 2 respectively.

The display features comprise a single piece back 8 and side wings each composed of panels 9 and 10 hinged respectively to an edge of the back and the top of a side 2 and interconnected by a fold line 11 so as to collapse inwardly when the lid is lowered, as shown in Fig. 5.

In the container of Patent No. 2,168,240 it was contemplated that the panels of the side wings would be held flat and upright, that is vertical, by means of merchandise packed against them, since the wings have some tendency to bend inward on account of the set given the cor-

rugated board along the line 11. In order to insure that the top will stand up with the wings flat and vertical irrespective of whether or not there is merchandise to hold up the wings or the back, we have devised fastening locks for the corners between wing and back which will be effective whether the display carton is full or empty.

In the form shown in Fig. 2 the lock comprises 10 tabs 14 and 15 respectively of any convenient shape; quarter circles are shown. The larger tabs 14 are made by cuts through back 8 around the entire tab except for one horizontal edge 14' which constitutes a permanent hinge. A vertical edge 14'' is on the fold line between back 8 and panel 9, so that when the tab 14 is set down horizontally it holds the wing against collapsing. At the same time tab 14 forms a small shelf on which individual items of merchandise M, Fig. 2, 20 from the contents of the carton, may be set, but the lock is effective whether or not the tabs are used as shelves. A smaller tab 15, cut from the wing, vertically hinged as at 15', and with upper horizontal edge 15'' at the level of hinge 14', is 25 swung inward to provide a rest for tab 14.

Since there are no parts to be removed, these tabs 14 and 15 are part of the blank and do not add any more pieces nor make the blank any more complex except for the necessary cuts to 30 allow the tabs to swing. Thus when the box is closed the tabs 14 and 15 simply lie in the respective panels to which they belong.

What we claim is:

In a display container comprising four upright walls, a bottom, a back which constitutes a top element when the container is closed, foldable side wings each attached to an end of said back and to the top of the adjacent side, said back and wings standing upright when set up for display, a locking tab cut out of said back and horizontally hinged to said back along one edge but cut free therefrom on all other edges, said tab being disposed horizontally when back and wings are set up for display and when so disposed 40 forming a shelf having one free edge abutting the inner face of the adjacent wing; a supporting tab for said locking tab, said supporting tab being spaced from the vertical junction of said wing and said back and being cut out of said wing on all but one side and hinged to said wing along a vertical line on said one side with the upper extremity of said supporting tab at the level of the horizontal position of said locking tab.
